H. W. ROUNTREE

WARDROBE TRUNK

Filed Jan. 5, 1923

UNITED STATES PATENT OFFICE.

HENRY W. ROUNTREE, OF RICHMOND, VIRGINIA, ASSIGNOR TO H. W. ROUNTREE & BROTHER TRUNK & BAG COMPANY, INCORPORATED, OF RICHMOND, VIRGINIA.

WARDROBE TRUNK.

Application filed January 5, 1923. Serial No. 610,875.

To all whom it may concern:

Be it known that I, HENRY W. ROUNTREE, a citizen of the United States, residing at Richmond, in the county of Henrico and State of Virginia, have invented certain new and useful Improvements in Wardrobe Trunks, of which the following is a specification.

My present invention has reference to improvements in wardrobe trunks in which is included a clothes presser or follower adapted for being utilized as an ironing board when it is removed from the clothes compartment of the trunk, and in which is also included a laundry bag, usually secured by straps or other means in the clothes compartment of the trunk, and my said invention primarily has for its purpose to provide an improved construction of laundry bag and clothes presser or follower attachment for wardrobe trunks simple and economical in construction, and having provision to provide for moving the follower board, the laundry bag and clothes hangers to the clothes compressing position, in unison, the laundry bag also acting as a dust-proof curtain for the hung garments, and the presser or follower board is adapted for holding the laundry bag entrance covering flap closed against being readily opened for access to the bag when the trunk is opened in the upright position for having access to the drawers thereof.

Another object of my invention is to provide, in a wardrobe trunk, a simple and inexpensive means for slidably supporting the laundry bag on the clothes hanger trolleys and for suspending the follower board on and to move with the laundry bag and at the same time hold the board in the desired mid-way position over the front face of the bag and to provide for readily disconnecting the said board from its suspension without disturbing the hanging of the laundry bag.

With other objects in view that will hereinafter be mentioned, my invention embodies the improvements in wardrobe trunks fully explained in the following detailed description, specifically stated in the appended claims and illustrated in the accompanying drawings, in which:

Figure 1 is a perspective view of a wardrobe trunk section with my improvements

operatively embodied thereupon, the trunk 55 being shown at the open position, the combined follower and ironing board with the rigid locking devices and the laundry bag being shown in their clothes pressing and dust protecting position. 60

Figure 2 is a perspective view of the laundry bag and the combined follower or ironing board, the latter being lifted from the rigid cross strip on the upper edge of the laundry bag. 65

Figure 3 is a perspective view of my improved construction of laundry bag.

Figure 4 is a perspective view of a combined follower and ironing board without the locking bolt devices. 70

Figure 5 is a detail central cross section of the laundry bag and the clothes presser or follower board.

In the drawings is illustrated a modern type of wardrobe trunk that comprises two 75 half sections so hung together, that, when opened and the trunk is supported in the upright position, as shown in Figure 1, the drawers that fill one compartment or trunk section and the clothes receiver formed in 80 the other section or compartment of the trunk have such relation that access to either of the said trunk compartments may be conveniently had.

The clothes compartment of the trunk is 85 shown with the usual trolley rods or hangers 2-2 secured to the upper ends of the opposite side members 20 of the clothes compartment and are arranged in the usual manner for supporting the conventional 90 type of clothes hanger devices 3 adapted for being slidably shifted along the trolleys when the different hangers with the clothes supported thereon are moved together and held under compression by the follower or 95 presser board in the usual way, and as will be clearly understood from Figure 1 of the drawings.

In my present construction of wardrobe trunk the laundry bag instead of being secured to the clothes compartment of the trunk by straps, hooks or the like is of substantially the full width of the clothes compartment and has its open upper or mouth end provided with the usual closure flap 40, 100 that portion of the upper end of the bag, of which the flap 40 forms a part being looped around and made fast to a rigid

cross or top strip 5, preferably a flat strip of wood, of a length substantially the width of the bag flap 40.

6 A metal hanger hook 6, such as is used on the clothes hangers, is attached to each end of the flat cross strip 5 and the said hanger hooks 6—6 provide for readily suspending the bag on the opposite trolley rods 2 when the bag is to be mounted within the 10 trunk as shown in Figure 1.

Metal angle stops 4—4 are permanently secured to that face of the strip 5 having the flap end of the bag looped thereover, the purpose of which will presently appear.

15 So far as described and shown my construction of laundry bag can be readily suspended from the trolleys 2 the same as a clothes hanger and when hung as shown in Figure 1, with its flap face outward, and 20 when the presser board is lifted therefrom the laundry can be readily placed into the mouth of the bag or removed therefrom. The laundry bag being substantially the full width of the clothes compartment it 25 serves as a curtain to protect the clothes, hung in the compartment back of the bag, from dust, and from being disturbed when placing laundry into or removing it from the bag.

30 The rigid cross strip at the upper back edge of the bag provides for conveniently hanging the presser board over the front face of the bag and to that end the said presser board is provided with a U shaped 35 metal hanger strip 7 that extends entirely across the inner upper edge of the board 70 and is adapted for snugly hooking over the rigid flat strip 5 on the upper edge of the bag as is shown in Figures 1 and 5, by reference to which it will also be noticed that 40 the stops 4—4 on the top cross strip of the laundry bag are so spaced that when the board 70 is hung, as shown, it is centered and held to such suspended position by its 45 opposite edges engaging the said stops 4—4. The upper edge of the board 70 has a finger member 8 for lifting the board from the laundry bag strip when access is desired to the bag or when the board is to be removed 50 and used for ironing purposes.

Some of the modern types of wardrobe trunks, now on the market are provided with horizontally disposed ratchets along the inner faces of the opposite ends of the 55 clothes compartment, for cooperating with laterally yieldable lock bolts on the presser board. In my preferred construction of presser board, as shown in Figure 1, the board is provided along the front face with a cross strip 10 of a length substantially the width of the clothes hanger compartment of the trunk and on this cross strip is mounted oppositely projected slidable lock bolts 60 11—11 whose outer ends project beyond the 65 ends of the strip 10, for engaging the ratch-

ets 12 at their respective ends of the clothes compartment.

The bolts 11 are suitably guided in end bearings 13 on the strip 10 and their adjacent inner ends are normally outwardly 70 pressed by a coil spring 14 mounted in a suitable housing 15 on the strip 10. The inner ends of the bolts terminate in downwardly projected finger grips 16 slidable in longitudinal slots 17 in the housing 15 and the grips 75 16 have their angled ends bent inwardly to reduce the danger of hooking into the garments in the trunk and also to prevent the ends of the pull grips from coming into touch with the fingers of the hands. 80

By providing the board with ratchet engaging lock bolts as stated and shown it is apparent that by pressing the follower board inwardly the laundry bag and the clothes behind it will be compressed and held to such condition by the ratchet and lock bolt devices and with the clothes held practically dust-proof by reason of the laundry bag completely covering the same, it being understood that the bag flap is held 90 practically locked against being opened so long as the follower board is moved up against the flap end of the bag as shown.

By suspending the follower board as shown it is apparent that by releasing the 95 lock bolts, done by pulling the finger grips together, the board can be quickly lifted off the cross strip on the upper end of the bag to permit of access to the bag and to the hanger garments. 100

By providing the bag with hangers as shown, the need of hooks for holding the bag in place, as is now the practice when using laundry bags with some types of wardrobe trunks, is avoided. The expense of fitting a bag on a trunk is lessened, easy access to and movement of the bag is provided for, the durability of the bag is increased and the need of an extra dust curtain for the clothes compartment is done away with. 110

While I prefer to use a presser board provided with ratchet engaging locking rods, as shown in Figures 1, 2 and 3, a plain board, particularly adapted for use as an ironing board and without the ratchet engaging locking device, may be used as shown in Figure 4, from which it will be noticed the said board also has the U shaped hook strip along the rear upper edge for fitting over the flat strip 5 on the upper edge of the laundry bag. 115

The U shaped member that extends along the full width of the board in addition to its function as a hanger, also serves as a reinforce to prevent warping of the said board. 120

What I claim is:

1. In a wardrobe trunk having a clothes compartment with a pair of hanging trolleys at the opposite sides of said compartment, a laundry bag of dimensions to substantial- 130

ly conform to said compartment and having a hanger strip at its upper end with means for hooking over said trolleys, and a follower board having means to hook over said hanger strip and being of less width than said hanger strip, means on said hanger strip for centering said follower board on the hanger strip and a latch member for securing the follower board in place to the sides of the trunk.

2. In a wardrobe trunk having a clothes compartment with a pair of hanging trolleys at the opposite sides of said compartment, a laundry bag of dimensions to substantially conform to said compartment and having a hanger strip at its upper end with means for hooking over said trolleys, a follower board having means to hook over said hanger strip and being of less width than said hanger strip, means on said hanger strip for centering said follower board on the hanger strip, a latch member for securing the follower board in place to the sides of the trunk, said laundry bag having a closure flap and said centering means being located on the flap side whereby said laundry bag will always be placed in such position

that said follower board will engage the flap side of said laundry bag and hold the flap closed.

3. In a wardrobe trunk of the character described and which includes a clothes compartment having garment hanger trolleys at the opposite sides of the said compartment; a laundry bag having means at the upper edge for slidably suspending it on the clothes hanger trolleys, said means including a flat cross strip, a presser board having a member that hooks over the said cross piece and means engaging the board and the trunk body for securing the board, the laundry bag and the clothes hangers to their compressed adjustment within the said clothes compartment of the trunk.

4. In a wardrobe trunk having a clothes compartment with a pair of hanging trolleys at the opposite sides of said compartment, a laundry bag having a hanger strip at its upper end with means for hooking over said trolleys, and a follower board having means to hook over said hanger strip, and a latch member for securing the follower board in place to the sides of the trunk.

HENRY W. ROUNTREE.
